UNITED STATES PATENT OFFICE.

WARREN V. JOHNSON AND ROBERT C. KEPNER, OF BLOOMSBURG, PENNSYLVANIA,
ASSIGNORS TO AMERICAN CAR AND FOUNDRY COMPANY, OF ST. LOUIS, MISSOURI,
A CORPORATION OF NEW JERSEY.

MINE-CAR RUNNING-GEAR.

1,183,983.

Specification of Letters Patent.

Patented May 23, 1916.

Application filed November 22, 1915. Serial No. 62,701.

To all whom it may concern:

Be it known that we, WARREN V. JOHNSON and ROBERT C. KEPNER, residing at Bloomsburg, Pennsylvania, and being citizens of the United States, have invented certain new and useful Improvements in Mine-Car Running-Gear, of which the following is a full, clear, and exact description, such as will enable others skilled in the art to 10 which it appertains to make and to use the same, reference being had to the accompanying drawings, which illustrate the preferred form of the invention, though it is to be understood that the invention is not limited 15 to the exact details of construction shown and described, as it is obvious that various modifications thereof will occur to persons skilled in the art.

In said drawings: Figure 1 is a transverse sectional view showing parts in section at the left and showing similar parts in elevation at the right; Fig. 2 is a fragmentary end view of a wheel; Fig. 3 is an end view of a journal box with the wheel and 20 axle removed; Fig. 4 is a longitudinal sectional view the section being taken on line 4-4 of Fig. 1.

This invention relates to new and useful improvements in what are known as tight 30 and loose running gears, especially adapted for use in mine cars, and comprises certain features of novelty in the construction and arrangement of parts, all as hereinafter 35 fully described and particularly pointed out in the claims.

The object of the invention is to provide a running gear for mine cars of maximum strength, in which one of the wheels of the assembly is secured fast to and rotatable 40 with the axle and the other wheel at the opposite end of said axle is held in position by suitable means passing through the axle, but not through the wheel, so that the wheel may be rotated independently of the axle. 45 The invention relates to means for connecting the journal-box to the car, means for utilizing substantially all of the lubricant which is injected into the wheel interior and a peculiar form of journal-box assem-

bled therewith, all as shown in the accompanying drawings.

Referring to the drawings, 1 indicates an axle which may be either of uniform diameter from end to end or of reduced diameter at its end portion, as may be desired. 50 2-2 indicate the journal-boxes, which are secured by means of through bolts 3 through outstanding flanges 4 of the journal-boxes, thence through longitudinally extending connecting straps 5, which are employed to 55 connect the pairs of wheels and journal-boxes together, and thence through the floor or sill of the car, and where a metal side is used, through the horizontal flange 6 of such metal side 7. 60

The journal-box is relatively deep and is provided at its inner portion, *i. e.*, the portion nearer the central longitudinal axis of the car with an oil cavity 8, which may be filled with waste or other suitable oil retaining means 9. The oil cavity 8 communicates through the passage 10 with the outer side of the journal-box, in which is preferably packed hair felt or other suitable oil retaining packing 11. The upper face 12 70

of the journal-box is recessed at 13, and in the recess 13 there is locked a depending flange 14 of said connection strap 5 before referred to, said flange coöperating with the recess 13 to lock the journal-box in position to the car body. The tight wheel 15, as it is called, is held in position by the bolt 16 passing through a hub portion 17 of said wheel and through an end portion of the axle 1, and the tight wheel may, or may not 80 be provided with a closed hub portion protecting the outer end of the axle and preventing the passage of dust to the interior of said wheel 15. Due to the connection bolt 16 passing through the wheel-hub and 85 axle, said wheel 15 necessarily causes the axle 1 to rotate with revolution of the wheel. At the opposite end of the axle the wheel 20 is rotatable on said axle and is held in position by means of the collar 21 and lynch pin 22, the latter projecting through an orifice in the axle as shown. The wheel 20 is illustrated as provided with a hub por-

tion 23, provided with the through perforation 24 by means of which and a suitable pin the wheel may be secured fast to the axle if desired, though in the assembly illustrated it is preferred that but one of the wheels shall rotate with the axle at all times and the wheel 20 be rotatable independently of the axle, as in rounding curves, etc.

The wheels may be identical in shape if desired, and in such wheels there is provided a hub cavity 26, adapted to hold oil or other suitable lubricant therein, which lubricant is fed through the valve 27 into said oil cavity 26, upon projecting the valve 28 inwardly in the direction of the arrow, against the pressure of the spring 29, said spring bearing against the head of the valve 28 at one end and against the shoulder 30 at its opposite end, and the valve stem projecting through the inner end of the valve cage. The inner end portion 31 of the hub of the wheel is of gradually reduced diameter and is provided with one or more lubricant passages 32 connecting with the chamber 26 and extending to and through the rear inner face of the wheel hub. Intermediate the hub of the wheel and the journal-box is a washer 35 adapted to provide a bearing surface for the wheel hub, which may be removed and a new one substituted to compensate for wear of the parts if desired. The lubricant passage 10 is in relatively the lowest part of the journal-box, and any lubricant which passes through the passage 32, after saturating the hair felt 11, will find its way through the lubricant passage 10 into contact with the waste or other filler 9 in the oil cavity 8, whereupon it performs its function in lubricating the axle 1. A passage for the lubricant through the wheel and into the journal-box is desirable in view of the fact that in most instances mine cars of the type to which the assembly herein illustrated is applied are of small size and access to the journal-boxes, except through the wheels as described, is decidedly inconvenient and as a consequence it has been found in practice that such journal-boxes have not been properly lubricated. Leading from the lubricant chamber 26 through the passages 26, lubricant may find its way to the axle 1, and it is evident that more or less of such lubricant will pass between the inner end of the hub and the washer 35 above referred to, thus additionally lubricating the axle while the space 40 between the washer 21 and the outer end of the hub of the wheel permits more or less movement of the loose wheel longitudinally of the axle, which movement necessarily carries a sufficient quantity of lubricant to the outer end portion of the axle.

What we claim is:

1. In a truck, a plurality of axles, a plu-

rality of journal boxes on each axle, each journal box being provided with a longitudinal recess, straps connecting said journal boxes in pairs, wheels secured to said axles by means interlocking with the wheels and axles, and each wheel being provided with an inner hub portion of reduced diameter extending into said journal boxes, there being communicating but separately formed lubricant chambers in the wheels and journal boxes.

2. In a truck, an axle, wheels on opposite end portions thereof, a securing pin adapted to lock each wheel in position, one of the pins passing through the wheel and the axle and one of the pins passing only through the axle, journal boxes in which said axle is freely rotatable, a lubricant reservoir occupying the greater portion of the lower part of each of said journal boxes, and packing in the outer ends of said journal boxes surrounding reduced inner flanges of said wheels.

3. In a truck, an axle, wheels having tapered hubs on opposite end portions of said axle, a securing pin adapted to lock each wheel in position, one of the pins passing through the wheel and the axle and one of the pins passing only through the axle, journal boxes in which said axle is freely rotatable, a lubricant reservoir occupying the greater portion of the lower part of each of said journal boxes, and packing in the outer ends of said journal boxes surrounding the tapered hub portion of said wheels.

4. In a truck of the tight and loose wheel class, an axle perforated at each end, a plurality of journal boxes thereon each of which is provided with a large lubricant cavity, an enlarged open end of which serves as a packing receptacle, and a conduit, as 10, establishing communication between the lubricant cavity and the packing receptacle, a wheel rotatable with the axle extending into one of said packing receptacles, and a wheel rotatable independently of and on said axle extending into another of said packing receptacles, and means extending through the perforations in said axle to lock one wheel immovably on the axle and to secure the other wheel rotatably on the opposite end of the axle.

5. In a truck of the tight and loose wheel class, a pair of spaced axles perforated at each end, a plurality of journal boxes on each axle each of which is provided with a large lubricant cavity, an enlarged open end of which serves as a packing receptacle, and a conduit, as 10, establishing communication between the lubricant cavity and the packing receptacle, means connecting said journal boxes in connected pairs, a wheel rotatable with each axle and extending into one of said packing receptacles, and

a wheel rotatable independently of and on each axle and extending into another of said packing receptacles, and means extending through the perforations in said axles to lock one wheel immovably on each axle and to secure another wheel rotatably on the opposite end of each axle.

In witness whereof we have hereunto set our hands in the presence of two witnesses.

WARREN V. JOHNSON.
ROBERT C. KEPNER.
